United States Patent Office.

NEWTON N. RUGG, OF GENEVA, ILLINOIS.

Letters Patent No. 91,568, dated June 22, 1869.

IMPROVED BAG-HOLDER.

The Schedule referred to in these Letters Patent and making part of the same.

To all whom it may concern:

Be it known that I, NEWTON N. RUGG, of Geneva, in the county of Kane, and State of Illinois, have invented an Improved Bag-Holder; and I do hereby declare that the following is a full, clear, and exact description thereof, reference being had to the accompanying drawings, and letters marked thereon, making a part of this specification, in which—

Figure 1 is a perspective representation of my improved bag-holder, as it is attached to a spout.

Figure 2, an elevation of the same, in position as when it is holding a bag in place.

The nature of the present invention consists in the use of elbow-levers, which are pivoted to a spout and support jaws for clamping a bag fast, and which are so arranged that a bail, also pivoted to the spout, can be made to hold the jaws up or down, as the case may require, as the whole is hereinafter fully shown.

E D represent elbow-levers, which I generally make of cast-metal, and which are pivoted to lugs G, projecting out from plates F, which are fastened to a spout, M.

The lower ends D of these levers support jaws K, which have such length as will nearly correspond with the width of the spout, and are used to clamp the mouth of a bag to it, cleats x being fastened to the lower end of the spout, to form shoulders, that no teeth or spikes are required on the jaws.

The upper ends E of the levers are made wider than at the pivot, in order that when a bail, A, is raised up, it will so clamp them against the spout as to hold the jaws K out from the cleats, for the purpose of permitting both hands to be used in placing the bag on the spout.

The lower ends D of the levers are also made wider

than at the pivot, in order that when the bail A is forced down, it will clamp the jaws K firmly against a bag.

This bail is pivoted to bolts I, projecting out from plates H, which are fastened to the spout M, and screw-threads of such length are cut on the bolts, that nuts J may be so adjusted as to cause the bail to clamp the elbow-levers D E more or less tightly, as the case may require.

A projecting loop, B, formed on the middle part of the bail, is used as a hand-hold, for the convenience of operating the device.

Operation.

All that is required, is to so raise the bail A, as to clamp the ends E of the levers against the spout.

The mouth of the bag is then placed over the spout M, as shown at fig. 2, and the bail so brought down as to clamp it firmly against the cleats x.

It will be seen from this that the holder is especially adapted to any kind of spouts, in elevators, mills, warehouses, &c., and that it is very substantial, and can be made at small cost.

Having thus described my invention,

What I claim, and desire to secure by Letters Patent of the United States, is—

In combination with the spout M, the elbow-levers D E, having jaws K, said levers being hinged to lugs G on the sides of the spout, and operated by the pivoted bail A, all arranged as herein shown and described.

NEWTON N. RUGG.
